INFLATING APPARATUS

Donald L. Spender, Cheshire, Conn., assignor to Scovill Manufacturing Company, Waterbury, Conn., a corporation of Connecticut

Filed Mar. 15, 1963, Ser. No. 265,557
3 Claims. (Cl. 137—224.5)

This invention relates to an inflating apparatus, especially useful for tire inflating stations and particularly to such a device which is completely automatic in operation.

In general, the object of the invention is to provide an inflating apparatus having improved reliability in action and which is comparatively economical to manufacture and assemble.

Another object is to provide an improved apparatus of the kind described wherein adjustable means, such as a control knob, can be manipulated to adjust the pressure in the delivery line accurately while the pressure is being indicated on a standard pressure gauge.

More specifically, an object of the invention is to control the cycling of the inlet valve by relatively simple means between the pressure-responsive device and the delivery conduit, which means requires no moving parts, such as relays, dash pots or the like.

A still further object is to provide a pressure-responsive switch which will usually be referred to as a pressure switch for directly controlling the supply of current either to a solenoid inlet valve for admitting air to the delivery conduit when the pressure in the tire is too low, or to another solenoid valve for exhausting air from such conduit when the pressure is too high—the operation in either case being automatic merely by the application of the air hose to the tire.

In the accompanying drawing, I have shown for purpose of illustration, one embodiment which the invention may assume in practice. In the drawing:

FIG. 1 is a diagrammatic view of one embodiment of my improved inflating apparatus; and,

FIG. 2 is also a diagrammatic view of a portion of the apparatus with the elements in position for exhausting air.

The apparatus shown in the drawing includes a supply of compressed air, such as a reservoir 10 which is connected to the delivery conduit through a solenoid-operated inlet valve 11. The delivery conduit as shown, includes a pipe 12 and a flexible air hose 13.

The solenoid inlet valve 11 is preferably of the type which opens when energized and closes when deenergized. Power for the solenoid is supplied from power lines 14 and 15 under the control of a pressure switch, generally designated PS. The switch PS includes a movable springy contact lever 16 which is mounted in a block 17 of insulating material and normally tensioned against an upper contact 18. There is also a lower fixed contact 19 normally spaced from the spring lever 16, and the contacts 18 and 19 are also mounted in the block 17.

For actuating the switch lever 16, there is employed a pressure-responsive actuator of the general type disclosed in the patent to Williams 3,045,704, which comprises a hollow chamber or cylinder 20, a block of closed cell foam material 21, such as foam rubber or foam plastic, secured as by adhesive at its lower end to the inner surface of the chamber and having a movable actuator pin 22 extending downwardly through a hole 23 in the foam material. Pin 22 is carried by a disc 24 secured to the upper end of the foam material 21 as by adhesive. Thus, on low pressure, the actuating pin 22 withdraws into the chamber 20 and on increase of pressure, the foam material contracts lengthwise to project the pin 22 downwardly from the chamber.

2

Provision is made for adjusting the block 17 carrying the switch contacts 16, 18 and 19 relative to the pressure-responsive unit or actuator pin 22. For this purpose, the block 17 is attached to a movable arm 25 having a flanged base 25a which can slide in a suitable guideway 26 in a stationary support bracket 27. The bracket 27 has a pair of laterally extending arms 28 and 29 in which is journaled an adjusting screw 30 having threaded engagement with the arm 25 for moving the same. The upper end of the screw 30 is provided with a suitable knob 30a for adjusting purposes. The upper arm 28 may be further extended to provide a platform 28a for supporting the hollow chamber 20 of the pressure-responsive actuator. As shown, this platform may actually form the bottom wall of such chamber.

The hollow chamber 20 is in communication with the delivery conduit through a connecting line which includes a flow restrictor 31 and a reservoir 32 between the flow restrictor 31 and the chamber 20. The flow restrictor 20 may be of any known type and is often referred to as a flow control valve. It may be adjustable as by means of a screw-threaded valve stem 33. The reservoir means is of predetermined volumetric capacity and may be in the form of a cylinder or merely a pipe having the desired dimensions. The combination of the flow restrictor and reservoir means retards the surging of air in either direction so that the pressure-responsive actuator does not move suddenly in response to a pressure drop or rise. The pressure gauge 34 is connected in the line between the flow restrictor 31 and the chamber 20.

Means are also provided for automatically exhausting air from the delivery line when the pressure in the tire is too high. The pressure-responsive actuator will respond to such higher pressure and push the movable switch arm 16 downwardly against contact 19. This will cause energization of the solenoid outlet valve 35 from power line 14, movable contact lever 16, stationary contact 19, wire 36 through the solenoid and back to power line 15 through wire 37, to cause opening of the valve 35. This valve is connected to the atmosphere by a pipe 38 in which there is preferably connected a flow restrictor valve 39 which may be similar to valve 31.

The operation and manner of using the device will now be readily understood. The delivery line is normally under the pressure which is desired as the maximum delivery pressure. This is initially determined by adjusting the screw 30 and thus the position of the switch contact elements 16, 18 and 19 relative to the actuating pin 22 of the pressure responsive device. When this is done, the gauge 34 will promptly indicate the pressure in the delivery line which will be static when the air is not being delivered. With this condition, the switch arm 16 will be held by the pin 22 in a neutral position as indicated in dotted lines in FIG. 1.

Now assuming the delivery hose 13 is applied to an under-inflated tire, the pressure in the reservoir 32 and chamber 20 will be reduced as air flows therefrom to the tire, whereupon the cellular material of the block 21 will expand to lift the actuator pin 22 and close the energizing circuit for the solenoid valve 11. In this case, current will flow from power line 14, through the switch elements 18 and 16, line 40 of the coil of the solenoid, and back through line 37 to power line 15. The valve 11 then opens allowing high pressure air from tank 10 to flow directly to the tire, and also to the chamber 20 under the retarding action of the valve 31 and reservoir 32. After a short interval of time, the pressure in chamber 20 will rise to cause the cellular block 21 to contract and project the pin 22 downwardly enough to break the contact 18, thus causing deenergization and closing of the inlet valve. If the pressure in the tire is still below the

maximum set on the gauge 34, the pressure in chamber 20 will again be reduced and the cycle repeated until the pressure in the tire, and thus the delivery line, reaches the desired maximum. In that event, the actuator pin is holding the movable switch contact away from the stationary contact 18. Everything then is in a state of equilibrium, but if it is desired to then adjust the delivery pressure to a different value, it is only necessary to adjust the screw 30 and watch the gauge 34.

Now if the pressure in the tire is higher than the desired pressure as reflected by the gauge 34, the pressure will build up in the chamber 20 so that the movable contact 16 closes on the bottom contact 19. This causes energization of the outlet solenoid valve 35 through the circuit already described and allows the air to be exhausted from the delivery line, reservoir 32 and chamber 20 under the retarding effect of the flow restrictor 39 so as to prevent any quick surges. This cycling action of the valve 35 will continue until the desired pressure is attained when the actuator pin 22 moves to the neutral position to cause closing of the valve 35.

As a result of my invention, it will now be apparent to those skilled in the art that an exceedingly reliable and economical apparatus is provided for inflating tires to the desired pressure. This pressure is easily adjustable by a simple control knob 30a which need not be calibrated, the pressure being merely reflected on a common pressure gauge. The cycling of the supply valve is determined only by the capacity of the reservoir means and the characteristics of the flow restrictor, thus avoiding the use of devices with moving parts which are not only more expensive, but less reliable in operation.

It will also be noted that if desired, only the pressure switch, gauge and reservoir will be required at the air delivery station and that the apparatus containing the solenoid valve can be located at a remote point inside a building.

What I claim is:

1. In an inflating apparatus the combination of
  - (a) an air delivery conduit adapted for connection to a tire or the like;
  - (b) a solenoid inlet valve connecting said conduit to a source of compressed air, and which is open when energized and closed when deenergized;
  - (c) a pressure switch connected in circuit with the solenoid valve and constructed and arranged such that current flows directly from the switch to said solenoid valve;
  - (d) a connecting line between said pressure switch and

said delivery conduit so that the pressure switch will respond to pressure changes in said conduit;

(e) means for adjusting said switch whereby a predetermined maximum delivery pressure is maintained in said connecting line; and

(f) means including said switch to automatically cycle the operation of said valve, said last named means controlling the cycling of said inlet valve by retarding the opening action of said pressure switch upon a surge of air into said delivery conduit at a pressure substantially higher than said predetermined delivery pressure, and also for retarding the reclosing action of said switch on a reduction of pressure in said delivery line, which means consists solely of a flow restrictor in said connecting line (d) and reservoir means of predetermined capacity between said flow restrictor and said pressure switch; whereby repeated charges of air may be supplied to said delivery conduit by the controlled cycling of said solenoid inlet valve until said predetermined maximum delivery pressure remains substantially constant in said delivery conduit.

2. In an inflating apparatus the combination defined in claim 1 together with a pressure gauge in said connecting line (d) between said flow restrictor and pressure switch whereby the pressure switch may be adjusted by reference only to said gauge to establish the predetermined maximum delivery pressure.

3. In an inflating apparatus the combination defined in claim 1 together with a solenoid outlet valve connected to said delivery conduit, means operated by said pressure switch in response to a predetermined high pressure in said delivery conduit for energizing said outlet valve to open the same, and a flow restrictor on the outlet side of said outlet valve for retarding the exhaust of air from said delivery conduit when said outlet valve is open.
